UNITED STATES PATENT OFFICE.

HENRY J. LAUZON, OF BATHGATE, NORTH DAKOTA.

AIR-BRAKE-APPLYING DEVICE.

1,186,918.

Specification of Letters Patent. Patented June 13, 1916.

Application filed May 15, 1914. Serial No. 838,735.

To all whom it may concern:

Be it known that I, HENRY J. LAUZON, a citizen of the United States, residing at Bathgate, in the county of Pembina, State 5 of North Dakota, have invented certain new and useful Improvements in Air-Brake-Applying Devices; and I do hereby declare the following to be a full, clear, and exact description of the invention, such as will enable others skilled in the art to which it 10 pertains to make and use the same.

This invention relates to an air brake applying device.

An object of the invention is to provide 15 for the automatic stopping of a train when the engineer thereof fails to regard a stop signal.

A further object of the invention is to provide means which may be set with the 20 stop signal to operate the said train stopping device.

With these and other objects in view, such as will appear as the description progresses, my invention comprises the combination and 25 arrangement of parts as herein set forth and subsequently claimed.

Referring to the drawing: Figure 1 is a rear elevation of a locomotive, showing my device in place thereon. Fig. 2 is an enlarged sectional view of the device showing the valve gate for allowing the air to flow from the air inlet pipe to the brake applying mechanism in open position. Fig. 3 is a similar view, showing the gate in closed 35 position. Fig. 4 is a plan view of the device. Fig. 5 is a section on line 5—5 of Fig. 3. Fig. 6 is an enlarged view of the trip mechanism showing the same in operative position in full lines and in inoperative position 40 in dotted lines. Fig. 7 is a side elevation of the device, showing the trip lever in engagement with the trip rod previous to the operation of the said trip rod. Fig. 8 is a bottom plan view of the device.

Referring to the drawing by reference characters wherein like parts are indicated by like numerals throughout the several views, the air inlet pipe is indicated by the reference character 1 to which is attached by 50 a cross pipe 2 the pipe 3 through which the air is allowed to flow to the air brake applying mechanism. In the pipe 2 is shown conventionally the present applying device 4 which is controlled by the engineer. My device is located directly beneath this present applying device 4 and comprises a valve 5

connected between the said pipes 1 and 3 by short pipes 6 and 7 which are connected at certain of their ends to the valve and at their other ends to T joints 8 and 9 of the pipes 1 and 3. This valve constitutes a casing 10 having apertures 11 and 12 which are in communication with the apertures in the pipes 6 and 7 to allow air to flow through the valve at the proper time. On the upper portion of the casing is formed a cylindrical projection 13 which is closed at the top and has an aperture 14 therein. Located directly beneath said projection is a downwardly extending projection 15 having a centrally located longitudinal hole 16 therein which communicates with a chamber 17 in the casing 10 and with the chamber 18 in the projection 13. Slidably mounted in these chambers 17 and 18 is a cylindrical valve 75 gate 19 to the lower end of which is attached an operating rod 20 which extends down through the hole 16 in the portion 15 and out beyond said portion through an aperture 21 in the lower end thereof. The lower end of this projection 15 is reduced in diameter and has mounted therein packing which surrounds the rod 20 and prevents the escape of air from the valve. The rod 20 is reciprocably mounted within the casing to cause the valve gate to be either pushed upwardly into the chamber 18 in inoperative position or downwardly into the chamber 17 to close the communication between the pipes 1 and 3 through the valve 5.

In order that the valve gate may be ordinarily kept within the casing 18 in its uppermost position there is formed on the outer side of the projection 15 at diametrically opposite points two hooks 22 and 23 to which are attached coil springs 24 and 25 which springs are at their ends attached to a cross arm 26 secured to the rod 20 at its lower end, the tendency of which is to keep the valve gate in its upper position.

On the lower end of the rod 20 is formed a spring clip 27 which co-operates with the trip rod 28 to hold the valve gate in its lowermost position or to release the clip 27 to allow it to be pulled upwardly by the springs 24 and 25. This trip rod 28 is rotatably mounted in a box 29 on the frame of a locomotive.

On the inner end of this rod 28 and projecting upwardly therefrom is a rod 30 having on its end an enlarged spherical portion 31 which is engaged by the clip 27 to hold

the said clip and consequently the rod 20 in its lowermost position.

On the opposite end of the rod 28 is formed a downwardly projecting lever 32 having an enlarged lower end 33 which operates with a trip lever 34 made of spring steel and pivoted as at 35 to a rigid vertical member 36 adapted to be secured to the tie beneath the rail and to the outside of the said rail when the member 34 is thrown in its horizontal position it will extend across the path or movement of the lever 32 and engage the same and cause the rod 28 to be oscillated to operate the valve gate 19. However, when this trip lever 34 is in its vertical position, it will not be in the path of movement of the lever 32 and therefore the valve gate 19 will not be operated. It is to be understood that this trip lever 34 may be operated in the same manner and together with a semaphore signal so that when the signal is set to stop a train the lever will also be thrown into such position that the lever 32 will be engaged to operate the valve gate.

On either side of the valve 5 and in the pipes 6 and 7 is located a hand valve 37 by means of which air may be shut off from said valve from either of the pipes 1 or 3. In operation, assuming that the valve is in such position as shown in Fig. 3, that is with the gate 19 within the chamber 17 to close the communication between the pipes 1 and 3 and is held in such position by the engagement of the rod 30 with the clip 27, as the train passes the trip lever 34 which has been previously set into its horizontal position the enlarged portion 33 of the lever 32 engages the trip lever 34 and causes the trip rod 28 to be oscillated within its bearing 29 which withdraws the rod 30 and its spherical head 31 from engagement with the clip 27. Immediately upon withdrawal of this rod 30 from the clip 27, the springs 24 and 25 pull the rod 20 upwardly by virtue of their connection with the cross bar 26 and consequently the valve gate 19 out of the chamber 17 in the casing 10 upwardly into the chamber 18 in the projection 13 and consequently communication between the pipes 1 and 3 through the valve 5 is opened, it being understood that the hand valve 37 has been previously opened. In order that there may be no compression of air between the gate 19 and the upper end of the projection 13 the aperture 14 is provided there which allows the escape of air there-

through and thus does not counteract the effect of the springs 25 and 24. The opening of this valve 5 and passing of air from the air supply pipe 1 through the pipe 3 to the brake operating mechanism causes the said brakes to be applied and the train thus automatically stopped. After the brakes have been applied and it is desired to again return the gate to its position in the chamber 17 so that it closes the communication between the pipes 1 and 3 the valves 37 are closed, which closes the communication between the said pipes 1 and 3 and thus releases the pressure of air from the said valve gate and the tendency thereof to hold it in its uppermost position. The gate may then be lowered and the remainder of the valves reset by the engagement of the rod 30 with the clip 27 in which the parts of the device are again in operative relation.

From the foregoing description it may be seen that I have provided a device which will automatically stop a train, and I have further provided a lever operating a trip rod carried by a locomotive to open the valve between the air supply pipe and the air brake applying mechanism to apply said brakes. I have further provided additional valves on each side of said first mentioned valves by means of which pressure within the said valve may be relieved so that the same may be readily operated to reset the mechanism.

I do not wish to be limited to the particular embodiment of my invention shown, but only so far as is necessary by the claim.

What is claimed is:

In an air brake valve, the combination with a casing having a pair of ports at the opposite sides thereof, of a plunger mounted in said casing and having a rod extending outwardly through one end thereof, a pair of resilient jaws on one end of the plunger rod adapted to be engaged by a suitable member to maintain the plunger in alignment with the said ports, a cross arm secured to the plunger rod and springs secured to the ends of the cross arm and to the casing, which springs are adapted to move the plunger out of alignment with the ports upon the release of the spring arms.

In testimony whereof, I affix my signature, in the presence of two witnesses.

HENRY J. LAUZON.
